CLAIM

The ornamental design for an analysis unit, as shown and described.

DESCRIPTION

Cross reference is made to copending U.S. design patent application Ser. No. 29/603,668 entitled "Analysis Unit" by Schulz et al., which was filed on May 11, 2017.

FIG. 1 is a perspective view of an analysis unit showing our new design;

FIG. 2 is a front elevational view of the analysis unit of FIG. 1;

FIG. 3 is a rear elevational view of the analysis unit of FIG. 1;

FIG. 4 is a right side elevational view of the analysis unit of FIG. 1;

FIG. 5 is a left side elevational view of the analysis unit of FIG. 1;

FIG. 6 is a top plan view of the analysis unit of FIG. 1; and,

FIG. 7 is a bottom plan view of the analysis unit of FIG. 1. The broken lines shown in the drawings illustrate portions of the analysis unit that form no part of the claimed design.
